HINGED VENTILATOR OF THE HOPPER
TYPE

John Marchbank, Glasgow, Scotland, assignor to
Frederick Braby & Company Limited, Glasgow,
Scotland, a corporation of the United King-
dom of Great Britain and Northern Ireland

Application February 2, 1937, Serial No. 123,667
In Great Britain March 9, 1936

1 Claim. (Cl. 98—99)

This invention relates to improvements in hinged ventilators of the hopper type which includes a ventilator sash having its lower horizontal rail hinged to the bottom rail of a ventilator frame so as to swing open on a horizontal axis into the apartment, collapsible side cheeks or wings being provided to close the space, when the sash is open, between the side rails of the sash and frame.

10 When the sash is open the side cheeks or wings and the sash present a hopper-like assembly.

Fig. 1 of the accompanying drawing is a transverse sectional elevation of a ventilator of the hopper type constructed according to an embodiment of the invention, the ventilator sash being shown open with the side cheeks extended. Fig. 2 is a fragmentary sectional plan of an end of the hopper assembly, the ventilator being shown closed with the side cheeks collapsed.

20 The embodiment of the invention illustrated includes a ventilator sash 1 and a ventilator frame 2. The lower rail of the sash is hinged or pivoted to the bottom rail of the frame and collapsible side cheeks or wings are provided to close the space, when the sash is open, between the side rails of the sash and side cheeks presenting a hopper assembly.

Each collapsible side cheek of the hopper assembly includes an outer or end blade 3 secured to the frame 2, an inner or end blade 4 secured to the sash 1 and intermediate blades 5 all strung upon the same pivot pin 6 which is located in alignment with the hinge or pivot pins of the sash. Alternatively the pins 6 may form the sash pivots or hinge.

The blades, 3, 4 and 5 are operatively connected by pins and cooperative slots so that when the sash is open or closed the intermediate and

inner blades are moved in succession to an extended or collapsed position.

The outer or end blade 3 and the intermediate blades 5 are each provided with a pin 7 having a head 8. The inner or end blade 4 and the intermediate blades 5 are each provided with a slot 9 which cooperates with an associated pin 7. The intermediate blades 5, except the blade adjacent to the outer blade 3, are each provided with a slot 10 having an open end.

When the sash is closed each pin head 8 is housed in an associated slot 10 whereby the blades may be nested close together.

I claim:

In a hopper ventilator, in combination, a stationary rectangular frame, a movable rectangular sash pivotally mounted in said frame, a pair of associated end blades which project forwardly on the opening side of the sash and are rigidly secured respectively to the frame and to the sash at each side thereof, a plurality of flat intermediate blades interposed between the blades of each associated pair of blades, the pairs of associated end blades and intermediate blades constituting projecting side cheeks of the hopper ventilator, a pivot pin for each side cheek, blade entraining pins each of which is secured to an intermediate blade, a similar blade entraining pin secured to one end blade at each side of the frame and sash, a close-ended slot formed in each intermediate blade, a similar close-ended slot formed in the other end blade at each side of the frame and sash, each blade entraining pin being operative in a close-ended slot, a head presented by each pin, and an additional slot having an open end formed in the blade adjacent to each head, each of said heads being operative in one of said additional slots.

JOHN MARCHBANK.
